(57) **CLAIM**

The ornamental design for an electronic cymbal, as shown and described.

DESCRIPTION

FIG. 1 is a perspective, bottom view of an electronic cymbal.

FIG. 2 is a side view of the electronic cymbal.

FIG. 3 is a top view of the electronic cymbal.

FIG. 4 is a side view opposite to the side view of FIG. 2, of the electronic cymbal.

FIG. 5 is a bottom view of the electronic cymbal.

FIG. 6 is a further side view of the electronic cymbal; and, FIG. 7 is yet a further side view of the electronic cymbal. The broken lines in the drawings are shown for illustrative purposes only and form no part of the claimed design.
